US00D886137S

(12) **United States Design Patent** (10) Patent No.: **US D886,137 S**
(45) Date of Patent: **** Jun. 2, 2020**

(54) **DISPLAY SCREEN OR PORTION THEREOF WITH ANIMATED GRAPHICAL USER INTERFACE**

(71) Applicant: **Delos Living LLC**, New York, NY (US)

(72) Inventors: **Barrett Brod Kaminer**, New York, NY (US); **Max Andrew Pollinger**, New York, NY (US); **Tarynne Blake Lopez**, Cranford, NJ (US); **dingane Richard St Arromand**, New York, NY (US); **Shivaun Ryan**, South Yarra (AU); **Chris David Hall**, Narre Warren South (AU); **Shaun Benson Stewart**, New York, NY (US)

(73) Assignee: **Delos Living LLC**, New York, NY (US)

(**) Term: **15 Years**

(21) Appl. No.: **29/628,153**

(22) Filed: **Dec. 1, 2017**

(51) LOC (12) Cl. **14-04**

(52) U.S. Cl.

(57) CLAIM

The ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof; and,

FIG. 7 is the seventh image thereof.

The appearance of the animated graphical user interface

sequentially transitions between the images shown in FIGS.

1-7. The process or period in which one image transitions to

another forms no part of the claimed design. The broken line

showing of the remainder of the graphical user interface and

display screen forms no part of the claimed design.
